UNITED STATES PATENT OFFICE.

JEROME W. PACKARD, OF MALDEN, MASSACHUSETTS, ASSIGNOR OF
ONE-HALF TO ALBERT M. ELLIS, OF SAME PLACE.

PERMUTATION-LOCK.

SPECIFICATION forming part of Letters Patent No. 550,641, dated December 3, 1895.

Application filed March 7, 1895. Serial No. 540,926. (No model.)

To all whom it may concern:

Be it known that I, JEROME W. PACKARD, a citizen of the United States, residing at Malden, in the county of Middlesex and State 5 of Massachusetts, have invented certain new and useful Improvements in Permutation-Locks, of which the following is a specification, reference being had therein to the accompanying drawings.

10 My invention relates to improvements in permutation-locks; and the object of the invention is to provide a lock of this character which shall consist of the fewest possible parts arranged in an extremely simple manner, 15 whereby the lock may be very easily and cheaply produced and will not be liable to get out of order, while at the same time the construction is such that the lock cannot be opened or operated by unauthorized persons.

20 The invention is illustrated in the accompanying drawings, in which—

Figure 1 is a face view of a padlock. Fig. 2 shows the body of the lock in plan. Fig. 3 is a view with the disk removed. Fig. 3^a is a sectional view. Fig. 4 is a plan view, and Fig. 5 is an edge view, of a modified form, 25 showing the invention as applied to sliding bolt-lock; Fig. 6, a sectional view of the same; and Fig. 7 is a detail view.

30 Referring to the form shown in the first three figures, A represents a frame or body portion preferably of disk shape, and B the hook or staple of the lock, which has one arm b journaled in an opening b' in the edge of 35 the disk and retained therein by a key b². The other end b³ of the hook rests in a second opening b⁴. This opening or slot b⁴ is open at one or both sides to permit the hook to be swung around upon its arm b as a pivot when 40 the retaining-plates are moved laterally in unlocking.

45 Preferably two side or retaining disks or plates C D are shown in the drawings, and these disks are connected by a central spindle or pin E, which passes through and is adapted to turn in a central opening e in the body portion. The disks are journaled upon the ends of the spindle, so that not only can the spindle turn in the body portion, and with it 50 the two disks, but each disk may be rotated

independently of the shaft and of the other disk.

In order to permit the disks to be moved laterally to clear the movable end of the hook, a slot d' extends radially from the opening e, 55 and this slot is less in width than the diameter of the opening, while the spindle has two of its sides x flattened, so that when these flattened sides are brought into line with the radial slot the spindle and disks may be moved 60 laterally to uncover the staple, which may then be turned.

The edge of the body portion may be provided with any suitable characters, and an arrow or line provided on the head e' of the 65 spindle, so that when the line or arrow points to a certain character the spindle will be in the proper position to permit lateral movement, as above described. The disks are also connected with the body portion, so that they 70 are each held against lateral movement, except when adjusted to a certain position. This result is accomplished by having an annular groove f in one part, (shown, for example, in the disk,) with a radial groove f' 75 leading therefrom, and a pin or projection f² from the adjacent part enters this groove, and it will thus be seen that each plate can at all times be rotated freely, but can only be moved laterally when the pin is in line with 80 the radial groove. Suitable characters are provided upon the edges of the disk, and when certain predetermined characters upon the disks and body are in line with each other and the arrow on the shaft-head points correctly 85 the plates can then be moved laterally and the device unlocked.

In the modified form shown in Figs. 5, 6, and 7 the body portion A' is shown connected by a rigid central spindle a to a door C, provided with a suitable spring-lock H, of any suitable or desired construction. The bolt I of the lock has secured rigidly to it a plate J, having an annular opening j. The retaining-plates C' D' are mounted upon the spindle 95 in the same manner as in the main form and have the same form of pin-and-slot connection with each other and with the head or body portion. The inner plate D' has an annular flange d², which engages the annular 100

opening in the plate J. It will thus be seen that so long as the disks are held against lateral movement the bolt is held securely against being unlocked, but when the disks 5 are rotated to bring them into the proper position to permit them to be slid laterally upon the spindle the bolt may be operated in the usual manner.

Having thus described my invention, what 10 I claim is—

1. A permutation lock comprising the frame, the retaining device movably supported therein, the spindle and the rotatable and laterally movable disk for locking said 15 retaining device against movement except when set at a predetermined position, substantially as described.

2. A permutation lock comprising the frame, the retaining device movably carried thereby, the disks rotatably and laterally movable upon said spindle, means for holding them against lateral movement except when at a predetermined position, and means for preventing the movement of one disk inde- 20

pendent of the other, substantially as de- 25 scribed.

3. A permutation lock comprising the frame, the retaining device, the spindle, having flattened sides, and the disk rotatably mounted upon the spindle, said flattened sides 30 permitting lateral movement of the disk upon the frame to release the retaining device, substantially as described.

4. A permutation lock comprising the frame, the retaining device, the spindle, the 35 disk rotatably and laterally movable of the frame, and the connection between the disk and the frame comprising an annular groove in one member with a radial groove leading into said annular groove, and a pin or pro- 40 jection from the adjacent member entering said groove, substantially as described.

In testimony whereof I affix my signature in presence of two witnesses.

JEROME W. PACKARD.

Witnesses:

M. E. SHAPLEIGH,

CHARLES H. WARNER.
